UNITED STATES PATENT OFFICE

WILLIAM J. SEELAND, OF ELIZABETH, NEW JERSEY, ASSIGNOR TO STANDARD OIL DEVELOPMENT COMPANY, A CORPORATION OF DELAWARE

BELL CAP

Application filed March 20, 1929. Serial No. 348,432.

This invention relates to improvements in bell caps for vapor-liquid contact equipment. A principal object of the invention is to provide a simple, effective device free from parts likely to get out of order and adapted for installation by a workman without the aid of a helper.

The invention will be fully understood from the following description read in connection with the accompanying drawings; in which

Fig. 1 is a vertical section through a bell cap embodying my invention;

Fig. 2 is a top plan view of the T-bolt shown in Fig. 1;

Fig. 3 is a bottom plan view of the chimney shown in Fig. 1;

Fig. 4 is a view similar to Fig. 1 but illustrating additional securing means; and

Figs. 5 and 6 are front elevations of the securing means.

Referring first to Figs. 1 to 3 inclusive, 1 denotes an inverted cup shaped member or bell having slots 2 arranged in it near the lower margin. The bell rests upon a supporting frame 3 commonly called a chimney. This consists of legs 4 carrying an outturned flange 5 at the bottom. Downwardly extending lugs 6 are formed on the flange and are adapted to be received in openings 7 in a plate 8, about a circular orifice 8' therein. Recesses 9 are provided at opposite points in the flange. It will be understood that the plate 8 is installed in the usual manner in a column or tower. As in common practice, there may be a number of plates arranged at different levels in the column or tower, each plate carrying a large number of bell caps.

The stem or shank 10 of a T-bolt passes through a central perforation 11 in the top of chimney 4, and a perforation 12 in the top of the bell. The stem is threaded at the top to receive a nut 13. The head 14 of the T-bolt is cut away at the top on one side to provide a flange 15. On the other side it is recessed at 16 to receive the edge of the plate.

In assembling the improved bell cap, the T-bolt stem 10 is first run through the perforation 11 in chimney 3 and the nut 13 is loosely secured at the top of the stem. This as-

sembly is placed over orifice 8' in plate 8 by first pushing flange 15 under the lower edge of the plate and recess 16 in the T-bolt head is then engaged with the edge of the plate. The end of the T-bolt head is received in a recess 9. The lugs 6 are seated in grooves 7.

When assembled in this way, the T-bolt cannot drop through the plate because it is centered by the chimney. Although the T-bolt has some freedom of motion this is not enough to permit the recessed end to become disengaged from the plate. The T-bolt when loosely mounted can easily be slipped through the opening 8'.

To complete the mounting of the bell cap, the nut 13 is removed, the bell slipped over the T-bolt stem, the nut replaced and screwed up tight.

In removing the bell cap, this procedure is reversed. The nut is taken off, the bell removed and the nut then replaced. The T-bolt is then disengaged from the plate and the assembly is lifted out.

It will be seen that both the mounting and dismounting of the bell cap can be easily effected by one workman. There is no necessity for a helper below the plate to hold a part of the bell cap while another workman above the plate fastens or unfastens it.

In the form of the invention shown in Figs. 4 to 6 inclusive the principle is the same as described above but additional securing or filler means are provided. These means comprise a slide 17 having an orifice 18 adapted to receive the cutaway end of the T-bolt and a rider 19 having a bifurcation 20 adapted to be set astride the cutaway end. The slide 17 has a lip 18' extending outwardly at its top.

In mounting this type of bell cap the rider is removed and the slide slipped back towards the center of the T-bolt. The cutaway portion should be of greater extent in this case than in the form shown in Figs. 1 to 3 so as to permit the rider to move far enough back not to interfere with slipping the T-bolt through the plate. When it has been slipped through, the slide is moved over so that its lip 18' rests upon the edge of the plate. The rider is then inserted between the slide and

the T-bolt head so that the slide cannot move back.

The form of the invention shown in Figs. 4 to 6 may be used if limited freedom of motion of the T-bolt in the plate opening, prior to tightening the nut, is objectionable for any reason.

Various changes and alternative arrangements may be made within the scope of the appended claims in which it is my intention to claim all novelty inherent in the invention as broadly as the prior art permits.

I claim:

1. A bell cap comprising a bell perforated adjacent its periphery and adapted to cover an opening in a plate, a bolt having a laterally slotted head adjoining the underside of the bell, the slot being adapted to receive the edge of the plate, and means associated with the shank of the bolt for drawing the bell and head together.

2. A bell cap comprising a bell adapted to cover an opening in a plate, a bolt having a laterally slotted head adjoining the underside of the bell, the slot being adapted to receive the edge of the plate, and means for securing the bell to the bolt with the head protruding from the bell.

3. A bell cap comprising a bell perforated adjacent its periphery and adapted to cover an opening in a plate, a bolt, the head of which adjoins the underside of the bell and is laterally slotted on one side to receive the edge of the plate, and is provided with a laterally extending flange on the opposed side on the opposite side of the slot from the bell, and means for securing the bell to the bolt.

4. A bell cap comprising a bell perforated adjacent its periphery and adapted to cover an opening in a plate, a bolt, the head of which adjoins the underside of the bell and is laterally slotted on one side to receive the edge of the plate and is provided with a laterally extending flange on the opposed side on the opposite side of the slot from the bell, filler means interposed between the ends of the flange, and means for securing the bell to the bolt.

5. A bell cap comprising a bell, a bolt, the head of which adjoins the underside of the bell and is provided with a flange, a frame associated with the shank of the bolt on the underside of the bell protruding from the bell, and means for securing the bolt to the bell with the head protruding beyond the frame.

6. A bell cap comprising a bell, a perforated frame engaging the interior of the bell protruding therefrom and adapted to straddle an opening in a plate, a bolt having laterally slotted head protruding from the frame adapted to receive the edge of the plate, and means associated with the shank of the bolt for drawing the bell, frame and head together.

7. A bell cap comprising a bell, a perforated frame engaging the interior of the bell protruding therefrom and adapted to straddle an opening in a plate, a bolt having a laterally slotted head protruding from the frame adapted to receive the edge of the plate, the frame being slotted to receive the laterally slotted head, and means associated with the shank of the bolt for drawing the bell, frame and head together.

8. A bell cap comprising a bell, a perforated frame engaging the interior of the bell protruding therefrom and adapted to straddle an opening in a plate, a bolt protruding from the frame, one side of the head of the bolt being laterally slotted to receive the edge of the plate and the opposite side of the head being provided with a flange, and means associated with the shank of the bolt for drawing the bell, frame and head together.

WILLIAM J. SEELAND.
